UNITED STATES PATENT OFFICE.

JOHN C. BOHMKER, OF BRADLEY, ILLINOIS, ASSIGNOR TO SEARS, ROEBUCK AND CO., OF CHICAGO, ILLINOIS, A CORPORATION OF NEW YORK.

PLOWSHARE.

1,416,937.

Specification of Letters Patent. Patented May 23, 1922.

Application filed March 27, 1919. Serial No. 285,558.

To all whom it may concern:

Be it known that I, JOHN C. BOHMKER, a citizen of the United States, residing at Bradley, in the county of Kankakee and 5 State of Illinois, have invented certain new and useful Improvements in Plowshares, of which the following is a specification.

The invention relates to plow shares, and has for its object the provision of a plow share 10 having a point of great strength so that it shall not become broken in use, and which at the same time is capable of effectively withstanding the excessive wear to which it is subjected in use.

15 In the accompanying drawings, Figure 1 is a perspective view of a plow share embodying the features of my invention. Figs. 2 and 3 are detached views of the share blade and landside. Figs. 4 and 5 are detached views of wear receiving members to be secured to the share blade and landside to protect them against wear. Fig. 6 is a sectional view of the completed share, taken in the plane of line 6—6 of Fig. 1.

20 25 As illustrated in the drawings, the plow share comprises a share blade 1 and a separately formed landside 2. The share blade is provided with the usual apertures 3 for receiving bolts for securing the share to 30 the mold board of a plow. Preferably said blade is made of a three-ply steel plate, presenting outer surfaces of relatively hard steel, while the landside is made of relatively soft steel, and the two parts are 35 adapted to be permanently secured together as by welding. To this end the landside is provided at its upper edge with an inwardly extending flange 4 and it gradually decreases in height toward its forward end 40 until it merges with its flange to form a flattened end plate 5. In Fig. 3 the shape of the landside and its flange is indicated by broken lines.

45 Before the share blade and the landside are secured together they are each provided at their forward ends with a wear plate of hardened steel. Thus, the share blade is provided with a plate 6 shaped as shown in Fig. 4. To receive the plate the blade is 50 first shaped to form a depression 7 (Fig. 2) at its forward end and the plate is then welded in place. Similarly the landside is provided with a member 8 (Fig. 5) which is angular in shape forming two wear plates 55 8^a and 8^b. The landside is shaped at its for-

ward end to form depressions 9 and 10 in its outer and under sides to receive the wear plates 8^a and 8^b, respectively, of the angular member 8, and the member is then welded in position on the landside. In order that 60 the plates 6 and 8^a and 8^b shall present with the adjacent faces of the share blade and of the landside a substantially flat surface, they are preferably made sharp or pointed at their rear ends, as shown at 11 and 12 (Figs. 65 4 and 5).

When the plate 6 and member 8 have been secured to the share blade and landside, respectively, the parts are ready to be assembled. This is accomplished by welding, the 70 parts being placed together in the proper relationship between suitable dies (not shown) and finally shaped and secured together to form the plow point which may then be ground to the desired finish.

75 As shown at 13 in Fig. 6, a portion of the metal of the wear plate 8^a is forced around the underside of the landside into engagement with the inner side thereof, thus further protecting the landside against wear. 80 Moreover, in positioning the parts for the final welding operation the share blade is so arranged with reference to the landside that its outer edge overlaps or abuts the upper edge of the wear plate 8^a. Thus the 85 landside becomes enclosed within a sheath of hardened steel formed by the share blade and member 8.

It will be apparent that I have provided a plow share of a very practical character, 90 as well as an advantageous method of making the same. The forward end of the landside constitutes a core of relatively soft steel, lending strength to the point to prevent breakage. Furthermore, the plate 6 95 and member 8 form wear plates of hard steel which serve to effectively protect the upper surface of the share blade, as well as the outer and under sides of the landside.

I claim as my invention:

1. A plow share constructed to provide a point having a central reinforcing metallic core and an outer wear-receiving sheath, said share comprising a landside of relatively soft metal constituting at its forward end the core of the point, a share blade of hardened material welded upon the upper side of the landside with a portion projecting beyond the outer side of the landside, and a wear-receiving member also of hard- 110

ened material and welded to the landside with a portion abutting the under side of said projecting portion of the share blade and the outer surface of such abutting portion flush with the outer edge of the blade and the outer surface of the landside rearwardly of said member.

2. A plow share constructed to provide a point having a central reinforcing metallic core and an outer wear-receiving sheath, said share comprising a landside of relatively soft metal constituting at its forward end

the core of the point, a share blade of hardened material welded upon the upper side of the landside, and a wear-receiving member also of hardened material and welded to the landside with a portion abutting the share blade and the outer surface of such abutting portion flush with the outer surface of the landside rearwardly of said member.

In testimony whereof, I have hereunto set my hand.

JOHN C. BOHMKER.
